UNITED STATES PATENT OFFICE.

ORLENCE D. ORVIS, OF NEW YORK, N. Y.

BLADE ADJUSTMENT FOR SAFETY RAZORS OF THE GILLETTE TYPE.

Application filed April 21, 1925. Serial No. 24,725.

This invention relates to improvements in safety razors and more particularly to a novel and improved blade adjustment for safety razors of the Gillette type.

5 Under ordinary circumstances, when positioning a safety razor blade between the head and guard, the angularity of the blade will depend on how tight or how much pressure is exerted on the center of said blade 10 when the head is threaded into the handle. When the blade is first positioned on the guard, it is normally straight but due to its resiliency or flexibility, the blade conforms to the curvature of the guard as the 15 handle is threaded in position. It becomes then a matter of guess work as to how much tension should be exerted on the blade in positioning it between the head and the guard so that the angularity of the edge of 20 the blade will best suit the individual user of the razor.

The object of my invention therefore is to provide a positive means whereby the angularity of the blade may be set or adjusted so that when new blades are substituted for an old one, the blade adjusting element will not be disturbed, thus permitting the individual to obtain the service suitable to his particular condition.

30 In order to more fully understand and appreciate my invention, reference is had to the accompanying drawing showing a preferred embodiment of my invention, wherein

35 Fig. 1 is a view of the safety razor when assembled, being partially in section to show the adjustment screw.

Fig. 2 is an enlarged sectional view showing the relation of the head and guard to the adjustment screw.

40 Fig. 3 is a vertical sectional view showing the assembly of the adjustment screw in the hollow, threaded stem of the razor.

45 Referring now to the drawings wherein like reference characters designate corresponding parts throughout the several views, 5 designates the head and 6 the threaded screw formed therewith which is adapted to pass through a central aperture in a razor 50 blade guard 7. The blade 8 is positioned between the guard and the head and becomes flexed when the internally threaded stem 9 is screwed into position against the lower face of the guard.

55 Under ordinary conditions, as the head is urged toward the guard, the blade is flexed

until it conforms to the curvature of the guard. At an intermediate position, however, if the threaded portion of the head is not screwed entirely into the stem, the edge 60 of the blade will be spaced somewhat from the guard, and thus a different effect and result is produced when shaving due to the angularity of the razor blade edge presented to the shaving surface. After a very 65 short time, the individual ascertains the proper adjustment of the blade when positioned on the guard and when it is desired to maintain this adjustment, the adjusting screw 10, threaded at its upper end 11, is 70 threaded into the stem 9 until the end of the adjusting screw engages the end of the threaded portion 6 of the head 5. When so positioned, it will be seen that the threaded portion 6 of the head cannot advance 75 further into the stem but may be detached therefrom with the guard.

The lower end 12 of the adjusting screw is preferably graduated so that the graduations may coincide with the lower end of the 80 hollow stem. Thus by rotating and threading the threaded screw into the internally threaded stem to different positions, the individual may regulate the extent to which the head 5 flexes or bends the blade to produce the desired angularity of the razor 85 blade. A handle 14 is telescopically positioned in the lower end of hollow stem, concealing the threaded screw 10. By simply removing the handle 14, the lower end of the 90 threaded screw may be rotated in either direction for the purposes and objects above set forth.

Having shown and described my invention, what I now claim as new and desire 95 to secure by Letters Patent of the United States is:—

1. A safety razor comprising a head, a shank thereon in threaded engagement with a handle, and a threaded and graduated rod 100 also in direct engagement with the said handle and adapted to meet and bind against the tip of the aforesaid shank, and a guard member adapted to rest between the said handle and an inserted blade.

2. A safety razor comprising a head, a shank thereon in threaded engagement with a handle, and a threaded and graduated rod 110 also in direct engagement with the said handle and adapted to meet and bind against the tip of the said shank, a tubular cover member adapted to be inserted within

the said handle and to receive within itself a portion of the said graduated rod, and a guard member and blade secured between the said head and the handle member, substantially as shown and described.

3. A safety razor comprising a head, a guard, an internally threaded stem, said head having a screw portion adapted to pass through the guard into the threaded stem whereby a razor blade may be flexed against the guard, an adjusting screw with-

in the stem, one end of said adjusting screw adapted to limit the movement of the threaded portion of the head, the opposite end of the adjusting screw being graduated and adapted to coincide with the lower end of the stem and a telescopic handle for said stem.

In testimony whereof, I have signed my name to this specification this 2nd day of 20 April, 1925.

ORLENCE D. ORVIS.
